STANISLAUS PRANIS, OF NEWARK, NEW JERSEY.

SHADE-BRACKET.

1,149,466.

Specification of Letters Patent. Patented Aug. 10, 1915.

Application filed November 7, 1914. Serial No. 870,725.

To all whom it may concern:

Be it known that I, STANISLAUS PRANIS, a citizen of the United States, and a resident of Newark, in the county of Essex 5 and State of New Jersey, have invented certain new and useful Improvements in Shade-Brackets, of which the following is a specification.

The objects of this invention are to provide an improved and adjustable shade bracket; to provide improved means for clamping the bracket in adjusted position; to prevent the clamping cam from jarring loose; to provide clamping means which 10 tend to displace the adjustable member in the plane of the base or supporting member; to clamp the adjustable member toward the base or supporting member, rather than away from it; to support the bracket 15 arm against wobbling; to thus clamp the adjustable member and prevent it from wobbling by a single locking member; to secure a simple, neat and inexpensive construction, and to obtain other advantages 20 and results as may be brought out in the following description.

Referring to the accompanying drawing, in which like numerals of reference indicate the same parts throughout the several 25 views, Figure 1 is a perspective view of a shade bracket embodying my invention; Fig. 2 is a front elevation of the same; Fig. 3 is a detail perspective view of the adjustable member; Fig. 4 is a transverse 30 section on line A—A of Fig. 2 looking in the direction indicated by the arrows, and Fig. 5 is a detail perspective view of an adjustable member showing a modified 35 form of locking means.

40 In the specific embodiment of the invention illustrated in said drawing, the reference numeral 1 indicates a base plate, which is preferably constructed of sheet metal and provided with suitable holes 2, 2 therein for 45 securing the same to a window frame or the like by means of screws (not shown). The base plate has bent over top and bottom edges 3, 3, that is, the edges are bent over toward the front and returned toward 50 each other parallel to the body portion of the base plate and spaced therefrom, forming guideways 4, 4. An adjustable member 5 is mounted in said guideways adapt-

ed to be slid to any desired position from one end of the base plate to the other. This 55 adjustable member comprises a slide plate 6 from which projects the bracket arm 7 preferably at right angles thereto. The slide plate is arranged flatwise of the base and of proper proportions so as to project 60 at its top and bottom edges behind the bent over top and bottom edges 3, 3 of the base plate, thus preventing the member 5 from becoming dislodged by passing outward between the bent over edges. However, the 65 adjustable member is readily removed when desired by drawing the slide plate longitudinally of the base plate and out of the end of the guideways 4, 4. The bracket arm 5 stands upon edge or transverse to 70 the guideways and is of less height than the slide plate 6 so as to project between the bent over edges 3, 3 of the base plate. Said arm preferably provides a socket or perforation 8 at a distance from the slide 75 plate 6 adapted to receive the end of the shade roller, and the outer end of the arm is turned upward and made narrow as at 9, so as to support the usual adjustable metal 80 curtain rods.

In order to prevent the adjustable member from sliding longitudinally of the base plate when not desired, I provide a locking member 10, which comprises in its preferred construction a cam 11 pivoted as at 85 12 flatwise upon the front side of the slide plate 6. One end of said cam is shaped into a suitable finger piece 13 for the convenient manipulation of the same, and the other end provides a cam edge 14. By 90 virtue of said cam edge the entire edge of the slide plate opposite from the cam edge will be seated firmly in its guideway 4 as the cam is turned to engage its adjacent bent over edge 3, thereby not only frictionally 95 preventing the slide plate from moving longitudinally of the base but also preventing it from wobbling. It will be noted that the slide plate is not forced outwardly away from the base plate at all, the pressure being principally a tensile strain in the plane of the body portion of the base tending to displace the slide plate in said plane or flatwise of the base plate and toward one of the bent over edges. Obviously the cam 105 may bear against either the top or bottom

bent over edge 3, and for purposes of illustration the same has been shown bearing against the top edge. Preferably said cam is pivoted substantially midway between 5 the top and bottom edges of the slide plate so that it may be reversed in operation and caused to bear against the lower turned over edge 3 of the base plate when so desired. Furthermore, the cam edge is preferably beveled toward the slide plate thereby allowing the same to gain a purchase between the bent over edge and the slide plate, pressing the slide plate positively toward the base plate to obtain greater frictional contact and rigidity. In this manner the slide plate is not only clamped edgewise toward one of the bent over edges but is also clamped flatwise against the base plate and especially at the opposite end from 10 that which is pressed against the bent over edge of the base. It will be understood by those versant in such matters that since the slide plate is positively prevented from wabbling the tendency for the cam to become loosened by the ordinary use of the device is reduced to a minimum, and furthermore the cam is retained in position by virtue of the pressure transverse to its direction of swing clamping the cam at its 15 outer end between the slide plate and the bent over edge of the base plate.

Obviously the curtain rod supporting end 9 may be omitted if desired, and in this case the adjustable member could be used at 20 either end of the shade roller and either side up, that is with the cam engaging either the top edge or bottom edge of the base plate. In this manner the length of adjustment or adaptability of the device would be 25 increased.

Furthermore, it is within the scope of the invention to provide opposite cam edges, one to engage each of the bent over edges of the base plate. Such a construction is shown in 30 Fig. 5 wherein the reference numeral 15 indicates an adjustable member comprising a slide plate 16 and a bracket arm 17. A locking member 18 is pivoted as at 19 upon said slide plate preferably midway between 35 the top and bottom edges, said locking member or cam providing opposite cam edges 20, adapted, when the slide plate is slid onto the base plate, to underlie the opposite bent over edges thereof. A finger piece 21 is 40 bent up from said locking member for the convenient manipulation of the same. In this construction I have shown both a slot 22 and a hole 23 in the bracket arm 17 whereby the arm may support either end of 45 the shade, it being obviously within the scope of the invention to perforate the arm in any way best adapted to the use to which it is to be put.

Detail modifications may be made in 50 manufacturing my improved shade bracket,

without departing from the spirit and scope of the invention, and I do not wish to be understood as restricting myself except as required by the following claims when construed in the light of the prior art.

70

Having thus described the invention, what I claim is:

1. A shade bracket providing in combination with a base plate comprising a body portion and bent over top and bottom edges, an 75 adjustable member having a slide plate adapted to underlie said bent over edges of the base plate and a rotary cam pivoted flatwise on said slide plate adapted to wedge between one of said bent over edges and the 80 slide plate to clamp the slide plate toward said body portion of the base plate when the cam is rotated in one direction and to release said slide plate when the cam is rotated in the other direction.

85

2. A shade bracket providing in combination with a base plate having bent over top and bottom edges, an adjustable member comprising a bracket arm a slide plate at substantially right angles thereto adapted to underlie said bent over edges of the base plate and a rotary locking member pivoted flatwise on said slide plate with a cam edge adapted to engage one of said bent over edges and clamp the slide plate toward the 95 opposite bent over edge when the locking member is rotated in one direction and to release said slide plate when the locking member is rotated in the other direction.

90

3. A shade bracket providing in combination with a base plate having bent over top and bottom edges, an adjustable shade supporting member having a slide plate adapted to underlie said bent over edges of the base plate and a rotary locking member pivoted 100 flatwise on said slide plate with a cam edge adapted to engage either bent over edge to clamp the slide plate toward the other bent over edge when the locking member is rotated in one direction and to release said 105 slide plate when the locking member is rotated in the other direction.

110

4. A shade bracket providing in combination with a base plate having bent over top and bottom edges, an adjustable shade supporting member having a slide plate adapted to underlie said bent over edges of the base plate and a rotary cam pivoted flatwise on said slide plate and having a beveled engaging edge adapted to wedge beneath one of said bent over edges of the base plate and to clamp the slide plate both toward the opposite bent over edge and toward the base plate when the cam is rotated in one direction and to release said slide plate when the cam is rotated in the other direction.

115

5. A shade bracket providing in combination with a base plate having bent over top and bottom edges, an adjustable shade supporting member having a slide plate adapted 120

125

to underlie said bent over edges of the base plate and a rotary locking member pivoted flatwise on said slide plate with opposite cam edges adapted to engage both bent over edges to clamp the slide plate against said base plate when the locking member is rotated in one direction and to release said

slide plate when the locking member is rotated in the other direction.
